INVENTOR

UNITED STATES PATENT OFFICE.

JONATHAN O. FOWLER, OF NEW YORK, N. Y.

SEALED, SAFETY, FOUNTAIN-INKSTAND.

1,303,468.

Specification of Letters Patent. Patented May 13, 1919.

Application filed November 10, 1914. Serial No. 871,238.

To all whom it may concern:

Be it known that I, JONATHAN O. FOWLER, a citizen of the United States of America, and a resident of New York, in the county 5 and State of New York, have invented a certain new and useful Sealed, Safety, Fountain-Inkstand, of which the following is a specification, the same being a full, clear, and exact description of the invention, such 10 as will enable others skilled in the art to which it appertains to make and use the same.

This invention relates to closures for receptacles adapted to hold liquids, and in particular to a closure means therefor that may be readily applied to vessels containing fluids and which, when inserted in the mouth thereof, or securely placed over the well thereof, will effectually preclude any of the 15 contents of the same from being spilled in case the container is accidentally overturned, and which will prevent evaporation of the liquid and will also continuously supply the fluid at the top of the closure as it may be 20 desired for use. While, owing to the peculiar construction of my invention, the container may be quickly refilled at any time required, yet by the employment of the same the receptacle may also be just as readily 25 hermetically sealed, as for purposes of transportation or storage for long periods of time, and it may be equally readily unsealed again and quickly placed in an operative 30 condition and ready for immediate use.

35 The device is easy of operation and efficient in action, while the simplicity of the same and the durability of the parts render it of low cost and of long life. The invention will be more particularly described with 40 reference to one embodiment thereof which is comprised in the preferred use of the same, as, in the present instance, in connection with inkstands, as shown in the drawings which accompany and form a part of 45 this specification.

Broadly stated my invention consists of a container having a neck, a diaphragm made of elastic material positioned above and extending across the neck, and a dip-cup supported by the diaphragm.

50 I also employ a closure means for the container comprising a device having a lower apertured portion extending across said neck and also having vertically disposed 55 means for attachment to the said neck, said

closure means further comprising a housing reduced in width at the top thereof and having a central orifice for the entrance of the pen and located entirely above the diaphragm. 60

The two parts of the said closure may also have engaging means whereby the periphery of the diaphragm may be pressed downwardly to form a liquid tight seal exterior of the opening of the neck, whereby the depression of the dip-cup by the pen will compress the air within the container and so force the ink up through the bore of the dip-cup to the mouth thereof. 65

In the embodiment of the invention illustrated in the drawings, Figure 1 represents a view in section of an article constructed according to my invention; Fig. 2 is a sectional view of the upper portion of another structure in which the invention is embodied; and Fig. 3 is a view in detail of another form of diaphragm which may be used at will. 70

Like letters of reference indicate like parts 80 in all the views.

Referring particularly to the drawings, A denotes an inkstand or container of the style that is provided with a neck. F² denotes one type of my preferably elastic attachment support which device forms the lower part 85 of my closure means and is adapted both to lie upon the top of an inkstand and is entered into or otherwise engaged with the neck thereof and formed with a threaded rim f. At or near the outer part of the attachment device, and mounted and extending entirely across the said neck, is preferably placed a practically horizontal diaphragm E which is preferably made of elastic material as sheet rubber and formed with 90 a central orifice, or it may consist of other flexible material as a concentrically corrugated metal disk, as E³ in Fig. 3. The attachment device is engaged with the container neck and projects over and exerts a 95 pressure upon the periphery of the diaphragm. Adjacent to the diaphragm I place a structurally independent ring or washer J, the central part of which washer preferably inclines upwardly around the opening thereof and terminates in an elastic ledge j, which washer serves to support a spring D' to partially relieve the diaphragm from the tension of the spring. This spring is intermediate the center of the washer and the 100

105 washer. 110

flange C^2 of a dip-cup C' and holds the dip-cup C' and diaphragm E engaged with the said cup in proper operative position.

The said dip-cup C' is formed with a bore 5 O and a tapered extremity C and an enlargement e , and an elastic ring K may be engaged with the same. The ring K , which may form a valve to prevent the ink from contacting with the diaphragm, preferably 10 projects far enough beyond the enlargement e to rest upon or against the seat formed by the edge of the down-turned part f^2 of the attachment F^2 , although with a little pressure the ring may be forced through the 15 said seat when this operation may be required for purposes of refilling the container. The attachment F^2 preferably has packing G interposed between the same and the neck of the inkstand.

20 I also provide a housing B' which forms the upper part of my closure means, which incloses the diaphragm, dip-cup, washer and spring, which housing is made with a thread 25 b' to engage with and work in the threaded rim f of the attachment device. The bore O at the tapered extremity C of the dip-cup may be hermetically closed by a seal H during shipment of the container. The housing B' is preferably formed with a down-turned 30 rim b^2 around the orifice L at the top of the same and the threaded lower part b' of the said housing comprises means engaging with portion f of the attachment device to exert a downward pressure upon the periphery of 35 the diaphragm to form a liquid tight seal exterior of the neck of the container, the stress being exerted between the lowest part of the housing and the neck contact portion of the attachment device. The housing B' 40 and the attachment device which together constitute the closure means are not necessarily structurally independent as, if desired, the closure means may be of unitary construction.

45 In cases where the contents of the container are designed to be left for a long time in storage, or to be shipped to far distant countries, the lower face of the diaphragm E and ring K may be coated with a plastic 50 material as paraffin or other non-corrosive coating, which is indicated in the drawings by the shaded parts e' and k , in order to prevent deterioration of the same. If desired, the spring D' , washer J and ring K may be 55 dispensed with, as the other elements of the structure will work in an operative manner. In cases where a seal H is used, the seal may be readily broken by pushing a hat pin through the bore of the dip-cup.

60 My device is a safety structure, inasmuch as should the container become overturned by accident when unsealed, no ink can escape therefrom as no air can enter the same except through the small bore of the dip-cup,

on which account there will be practically 65 no evaporation of the ink. When the dip-cup is depressed, just the right amount of ink covers the pen on account of the automatic or fountain property of the device, and the article will be very durable as the 70 working parts of the same are of simple construction and are at all times protected from the action of the fluid held by the container.

I wish it to be understood that I do not desire to be limited to the exact details of 75 construction shown and described, for obvious modifications will occur to a person skilled in the art.

What I claim as my invention is:—

1. In a device of the class described, a container having a neck, a horizontally disposed diaphragm mounted upon and extending entirely across said neck, a dip-cup having a flange at its upper portion, an apertured washer mounted adjacent the diaphragm, a spring intermediate the central portion of the washer and the flange of the dip-cup, said washer supporting said spring to partly relieve the diaphragm from the tension of the spring, a housing to inclose the diaphragm, dip-cup, washer and spring, and a threaded attachment positioned on and extending over the container neck to engage the housing.

2. In a device of the class described, a 95 container having a neck, a diaphragm which is positioned in a practically horizontal plane and is located above the neck and extends across the latter, a dip-cup supported by the diaphragm, an apertured housing 100 superimposed on the diaphragm and having engaging means at the lower part thereof, an apertured attachment device lying over and extending across the neck and having vertically disposed means to contact with 105 the latter, said device also having engaging means to co-act with the engaging means of the housing, the said two engaging means being located above and exterior of the opening of the neck, whereby the periphery of 110 the diaphragm may be pressed downwardly to form a liquid tight seal exterior of the opening of the said neck, the stress being exerted on the periphery of the diaphragm between the lowest part of the housing and the 115 neck contact portion of the attachment device.

3. In a device of the class described, a container having a well, a diaphragm positioned above and extending across the well, 120 a dip-cup supported by the diaphragm, and a closure means comprising a device having a lower apertured portion extending across said well and also having means for attachment to the said container, said closure 125 means further comprising a housing reduced in width at the top thereof and located entirely above the diaphragm, said closure

means also having engaging means whereby the periphery of the diaphragm may be pressed downwardly to form a liquid-tight seal exterior of the opening of the well.

5 In testimony of the foregoing specification I do hereby sign the same in the city

of New York, county and State of New York, this 2nd day of May, 1914.

JONATHAN O. FOWLER.
